UNITED STATES PATENT OFFICE.

FRANK K. RITTENHOUSE, OF CHICAGO, ILLINOIS.

CUT-OFF VALVE-GEAR FOR ENGINES.

SPECIFICATION forming part of Letters Patent No. 643,203, dated February 13, 1900.

Application filed June 12, 1899. Serial No. 720,164. (No model.)

To all whom it may concern:

Be it known that I, FRANK K. RITTENHOUSE, a citizen of the United States, residing in Chicago, in the county of Cook and 5 State of Illinois, have made certain new and useful Improvements in Cut-Off Valve-Gears for Steam-Engines, of which the following is a specification, reference being had therein to the accompanying drawings, and the letters of reference thereon, which form a part of this specification.

This invention relates to an improvement in that class of cut-off mechanism employed in the construction of Corliss engines, and 15 particularly in the mechanism shown in Patent No. 505,153, granted September 19, 1893; and it consists in the attachment to the bent end of the rods which actuate the steam-inlet valves of springs arranged to serve as 20 cushions against the hubs of the pivoted trip-arms to which the bent end of said rods are connected. Heretofore in the use of such cut-off mechanism the contact of the hollow or curved portion of said valve-actuating rods 25 against the hubs of said trip-arms caused pounding, and therefore unnecessary noise; and the object of this invention is to cushion said parts, and thereby prevent direct pounding, and thus avoid unnecessary noise.

30 In the accompanying drawings, Figure 1 is a side elevation of an engine-cylinder and the cut-off mechanism thereto attached. Fig. 2 is a detailed side view of one of the steam-inlet valve- rods and connected trip-arm, 35 showing the application of the cushion-spring to said rod. Fig. 3 is a plan view of the same, also showing a portion of the wrist-plate to which said trip-arm is pivoted. Fig. 4 is a cross-sectional view of Fig. 2 on line 11. Fig. 40 5 is a detailed perspective of the cushion-spring, and Fig. 6 is a cross-sectional view of Fig. 2 on line 22 looking toward the left.

Similar letters of reference refer to similar parts throughout the several views of the 45 drawings.

Referring to said drawings, A represents an engine-cylinder having attached thereto and arranged in conjunction therewith the usual wrist-plate P, eccentric-rod E, steam- 50 inlet valve-stems V V, bell-cranks L L, connected with said stems, trip-arms B B, piv-

totally connected to said wrist-plate, rods R R, which are known as the "steam-rods," arranged connecting said trip-arms with said bell-cranks, dash-pots G G, rods F F, arranged connecting the said bell-cranks with dashes in said dash-pots, and arms carrying rollers J J, arranged in the path of one branch of the trip-arms B B and controlled in their position relative to said trip-arms by means 55 of governor-rods K K. The ends of rods R R, which connect with trip-arms B B, are bent as shown, and in their actuation their movement is such as at intervals to fold said rods down upon the hubs of said trip-arms, bringing 60 the hollow of the bend of the rods to rest upon said hubs.

The cushion-springs S comprise two parallel curved bars, connected at one end by a hollowed or curved cross portion, and are applied to rods R by placing their cross connecting portion under the rods adjacent to their connection with trip-arms B, by bringing their parallel bars to coincide with the opposite lower sides of rods R in such manner that 70 their curved portion will be adjacent to the bend of the rods and a little distance below the hollow of such bend, (see Fig. 2,) and by clamping their extending ends to the sides of the rods by placing them in opposite pockets of clamp-collars C, placed on said rods, and as a means of preventing said clamp-collars slipping back on said rods set-collars, as shown at D, may be employed. In the actuation of said rods and trip-arms when they 75 fold the springs S will engage against the hubs of the trip-arms, and thus cushion the stroke incidental in such movement. Adjustment of said springs is made by moving clamp-collars C along on rods R, which causes 80 the curved connecting portion of the springs to move up or down a limited distance on the portion of the rods where such cross portions contact, thereby changing the relative position of the springs adjacent the bends of the 85 rods to be a less or greater distance below the 90 hollow of the bends.

Having thus described my invention, what I claim as new and useful, and desire to secure by Letters Patent, is as follows:

1. In the herein-described cut-off mechanism for engines, the combination with the

steam-inlet valve-actuating rods, and the trip-arms connected therewith, of the springs attached to said rods and adapted to form a cushion at the place of contact of said rods 5 against the hubs of said trip-arms.

2. In the herein-described cut-off mechanism for engines, in combination with the rods R and arms B the springs S and their clamp-

attaching collars C substantially as and for the purpose specified. 10

Signed at Chicago, in Cook county, State of Illinois, this 20th day of May, 1899.

FRANK K. RITTENHOUSE.

In presence of—
M. F. RITTENHOUSE,
E. J. OSTRANDER.
